PAINT CAN ATTACHMENT FOR POURING AND SUPPORTING A BRUSH OR THE LIKE

David F. Jorgensen, Pasadena, Calif.

Application June 12, 1958, Serial No. 51,313

Term of patent 14 years

(Cl. D9—2)

Fig. 1.

Fig. 2.

Fig. 3.

Fig. 4.

Fig. 5.

Fig. 1 is an elevational view of one side of a paint can attachment for pouring and supporting a brush or the like showing my new design;

Fig. 2 is an elevational view of the other side thereof;

Fig. 3 is a front elevational view;

Fig. 4 is a rear elevational view; and

Fig. 5 is a top plan view.

I claim:

The ornamental design for a paint can attachment for pouring and supporting a brush or the like, as shown.
